UNITED STATES PATENT OFFICE.

GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR INSERTING FASTENINGS.

1,262,775.

Specification of Letters Patent. Patented Apr. 16, 1918.

Application filed September 5, 1913, Serial No. 788,193. Renewed October 17, 1916. Serial No. 126,202.

To all whom it may concern:

Be it known that I, GEORGE GODDU, a citizen of the United States, residing at Winchester, in the county of Middlesex and 5 State of Massachusetts, have invented certain Improvements in Machines for Inserting Fastenings, of which the following description, in connection with the accompanying drawings, is a specification, like reference characters on the drawings indicating like parts in the several figures.

This invention relates to machines for inserting fastenings and particularly to machines for inserting previously formed fastenings, although it will be apparent that 15 many of the novel features of the invention are of general applicability in the art to which the invention relates.

The invention is herein shown as embodied in a machine for inserting previously formed fastenings which is provided with a plurality of sources of fastening supply and a plurality of fastening guides leading from the sources of supply, but it will be 25 understood that the invention is not restricted to use with a machine having more than a single source of fastening supply.

In the machine in which the invention is shown as embodied, mechanism is provided 30 for automatically selecting and presenting for insertion that kind of fastening from the plurality of sources of supply which is particularly adapted for the portion of the work in which it is to be inserted. In this 35 machine, which is of the type known as "loose nailing machine," two raceways conduct nails of different lengths from two nail pots and the automatic mechanism operates to supply a short nail or a long nail, in accordance with the demands of the work, so 40 far as thickness is concerned.

In nailing boots and shoes with nails of the kind which this machine is particularly adapted to handle, it is important that the nail project through the work far enough 45 so that as it is driven the point may be properly clenched upon the side of the work remote from the head. The machine herein shown is so constructed that, when adjusted 50 with respect to the different lengths of the nails in the two raceways, it will supply a short nail so long as a short nail can properly be clenched and will supply a long nail

when the thickness of the work is such that sufficient clench would not be provided with 55 a short nail. It sometimes happens that it is desirable to drive a long nail when the automatic mechanism would supply a short nail and one of the objects of this invention is to provide means whereby the operator 60 may at will so vary the operation of the automatic mechanism that a long nail will be supplied when the normal operation of the automatic mechanism would cause, a 65 short nail to be supplied.

In the machine herein shown, a single treadle operates both to bring the work support into its operative work supporting position and to actuate the mechanism for inserting fastenings, the construction and mode of operation of the single treadle being more fully shown and described in my prior Letters Patent No. 1,011,941 granted December 19, 1911. In changing the nails in the nail pots from one kind or length to another, it is necessary not only to remove the nails in the nail pots, which can easily be done by taking off the nail pots, but also to remove the lines of nails which have accumulated in the raceways. The usual 70 procedure in emptying the raceways is to run the machine without presenting work to be nailed, the operator either catching the nails in some receptacle as they are thrown out or allowing them to be thrown out upon the floor. It will be observed that when a single treadle is employed to raise the work 75 support and actuate the inserting mechanism the work support will be in such position that it will interfere with the discharge of the nails from the raceways when it is desired to empty the raceways.

A further object of the invention is to provide independent means for actuating the inserting mechanism whereby, whenever it is desired the machine may be run without placing the work support in work supporting position. This means is preferably so connected to the means for manually controlling the shifting of the raceways that by a single continued movement of said manually operated means the raceways may be shifted and the fastening inserting mechanism then actuated. Moreover the means for manually controlling the shifting of the raceways is preferably so related to the

means for raising the work support and actuating the inserting mechanism that both may be controlled by a single foot of the operator.

5 In the accompanying drawings—

Figure 1 is a side elevation of a machine embodying the invention, part of the standard of the machine being shown as broken away to disclose the structure of the connections between the work support and its various operating mechanisms;

Fig. 2 is a side elevation of the raceway shifting mechanism, showing the parts in the positions which they assume when the raceway is set to deliver short nails;

Fig. 3 is a perspective detail showing the connections between the treadles and the parts which they control;

Fig. 4 is a detail view of the clutch actuating connections, this view showing the side of the machine opposite to that shown in Fig. 1, and

Fig. 5 is a detail view showing the connection between the raceway and its shifting mechanism.

The machine in which the invention is shown as embodied is of the type more fully described and illustrated in United States Letters Patent to George Goddu No. 1,030,775, granted June 25, 1912, the means for controlling the movements of the work support between work receiving position and work supporting position being illustrated and described in the Letters Patent to George Goddu No. 1,011,941 hereinabove identified, and the mechanism for shifting the double raceway from short nail position to long nail position and vice versa being illustrated and described in a co-pending application of Fred L. MacKenzie, Serial No. 788,194, of even date herewith.

In the machine herein illustrated, as in the machines of the said Letters Patent hereinabove referred to, a raceway having a plurality of nail guiding grooves, or a plurality of connected raceways, is so controlled by variations in thickness of the work presented to the machine in position to receive a nail that, when the work exceeds a thickness for which a short nail is suitable, the raceway or raceways will be moved into position to cause a long nail to be delivered to the inserting mechanism, and vice versa. To this end the machine herein illustrated, like the machines disclosed in the said Letters Patent, comprises means for gaging the thickness of the work, which for convenience, is the horn or other work support and the abutment against which the horn presses the work, and means by which variations in the position of the movable member of said gaging means will so affect the angular position of a double pawl arranged to coöperate with a slide connect-

ed to the raceway or raceways that, when the thickness of the work requires a short nail, the pawl will be tipped in one direction and will engage and force said slide and raceway into position to deliver short nails and when the thickness of the work requires a long nail the pawl will be tipped in another direction to cause the raceway to be moved into position to deliver a long nail.

For convenience in comparing the machine herein disclosed with those shown in the prior patents hereinabove referred to, similar reference numerals will be attached to similar parts where these parts have not been much changed or are not associated with parts which have undergone much change. The pawl carrying slide 280, upon which is mounted the double pawl 502, is reciprocated to bring said pawl into and out of engagement with one or the other of two shoulders 302, 306, upon a horizontal slide 304, by connections with a bell crank lever 182, comprising a rack 294 mounted upon said slide 280, which rack is engaged by a segment rack 296 upon an arm 298 of said bell crank 182. Another arm of said bell crank 182 carries a cam roll which enters the cam groove 184 in the cam wheel 48 upon the main shaft 20 of the machine. The connections between the slide 304 and the double raceway 264 comprise, as shown in the Letters Patent hereinbefore referred to, oppositely threaded rods 308, 310, connected by an adjusting nut 312, the rod 308 being pivotally connected to the lug 314 upon the side of the double raceway. The rod 310 receives in an opening at one end an eccentric pin carried on the lower end of the rock shaft 318 mounted in a bearing on the bracket 272, said rock shaft having formed upon its upper end a pinion 320 with which meshes a segment rack 322 (see Fig. 5) formed upon the end of the rock arm 324 which is clamped upon the upper end of the rock shaft 326 also mounted in a bearing in the bracket 272 and carrying at its lower end a segment gear 328 which meshes with rack teeth 330 formed upon the slide 304, the rack teeth 330 being formed at an inclination to the slide bar 304 and the bearings for the rock shafts 326, 318 being correspondingly inclined, this inclination serving to prevent binding when the inclined raceway is moved. The shifting movement of the slide 304 is sufficient to turn the eccentric pin upon the shaft 318 around from one dead center to the other with respect to the rod 310 so that the raceways are positively shifted and positively held in the positions into which they have been shifted.

The parts thus far described are substantially the same as the corresponding parts shown in the patent to Fred L. MacKenzie

hereinabove referred to, with the exception that the slide 280 is now provided with an overhanging yoke member 600 which has formed in its split lower end a bearing for the pivot pin 602 of the double pawl 502, said pin being clamped in said yoke by a set screw 604. As in the machine shown in the said patent to MacKenzie, the double pawl 502 has attached to, or forming part 10 of it, a semi-circular piece (not shown) which provides upon opposite sides of the axis of said pawl shoulders which coöperate with dogs 536 and 538 upon the pawl tipper 606, which differs somewhat in its construction and in its connections to the work thickness gaging means from the corresponding part shown in the said Letters Patent to MacKenzie. The operation of said pawl tipper, so far as the tipping of 15 the pawl is concerned, is substantially identical with the operation of the corresponding part of said Letters Patent to MacKenzie. The pawl tipper 606 herein shown comprises two arms 608, 610, which carry 20 respectively the dogs 536, 538, and a circular body portion provided with a hub mounted to turn freely upon a shaft 614.

The pawl tipper is so arranged that it is normally in short nail position, being yieldingly maintained in this position by a 30 spring 636 which is connected at one end to a screw or stud 638 upon the bracket 272 by which the raceway shifting mechanism is carried, and at its other end is bent down 35 so that it enters a socket 640 in the outer face of a bell crank lever 642 fulcrumed upon a stud 644 and having at its forward end a short rack 646 which engages teeth 648 in the periphery of the circular body 40 portion of the pawl tipper 606. Between the stud 644 and the pawl tipper 606 the arm of the bell crank 642 is provided with an opening which receives a stud 650 serving as a stop for the vertical movements of 45 said arm, the opening being larger in diameter than the stud 650, whereby movement of the arm sufficient to rock or permit the rocking of the pawl tipper between its two pawl tipping positions can take place. 50 The pawl tipper may be moved into its long nail position either by manual means herein to be described, or automatically in accordance with the demands of the work. The means for effecting the movement of 55 the pawl tipper in accordance with changes in the thickness of the work which require a long nail, are operated through connections with the horn 22 or other work support; said connections being fully described 60 in the copending application of Fred L. MacKenzie hereinabove identified.

If it is desired to deliver a long nail when the work is not of such a thickness that the long nail would be automatically supplied,

the raceway or raceways may be shifted into 65 position to deliver the long nail by manually controlled means now to be described. The bell crank lever 642 hereinabove referred to has a second arm 676 having a stop face 678 over which hooks a dog 680 pivotally connected to an arm 682 of another bell crank fulcrumed at 684 upon a rearward extension of the bracket 272; said dog being provided with a slot 686 guided upon a stud or screw 688 for limited longitudinal 70 movement. A second arm 690 of the dog operating bell crank is formed with a vertical bore through which slides a rod 692. The rod 692 also passes through a vertical bore in a lug 694 projecting laterally from 80 a socket link 697 forming a part of the connections between the starting treadle 3 and the clutch, said connections comprising a lever 380 and other parts more fully shown and described in the Letters Patent to George Goddu, No. 1,030,775 hereinabove referred to. A spring 696 surrounding the rod 692 and located between the lug 694 and the arm 690 tends to keep said lug and arm in separated relation. A clamp collar 90 95 698 clamped upon the rod 692 below the lug 694 is adapted to engage said lug and, through the connections hereinabove referred to, to trip the clutch and start the machine. During the first part of this movement of the rod 692 the bell crank lever 690, 682 will be rocked to draw back the dog 680 to throw the pawl tipper into its long nail position. The rod 692 is connected at its lower end by an adjustable clamp 700 to a second rod 702 pivotally connected at 704 to a second treadle 706 fulcrumed in the base of the machine, said rod 702 being guided through a sleeve 708 formed in the connections between the treadle 3 and the 100 link 697. The front end of the treadle 706 is normally maintained in its elevated position by the action of the spring 710 surrounding the rod 692 and confined between a clamp collar 712 upon said rod and the 105 bracket 714 projecting from the back of the standard 4. The treadle 3 is normally maintained in its elevated position by a spring 262 confined between a collar 261 upon the rod 260 and the said bracket 714. 110 115

From the foregoing description it will be seen that, when the horn has been raised and the machine started by depressing the treadle 3 in the usual manner, if it is desired to deliver a long nail and the position 120 of the work thickness gaging mechanism is not such that a long nail will be automatically furnished, the pawl tipper can be thrown into its long nail position by simply depressing the forward end of the treadle 125 lever 706. Furthermore, if it is desired to start the machine without raising the horn, continued depression of the forward end of

the treadle 706 will serve also to start the machine. Owing to the connections above described between this treadle lever and the means for manually controlling the shifting 5 of the raceway, the machine, when started by this treadle lever, will deliver long nails. If it is desired to start the machine without raising the horn and have the machine deliver short nails, this may be done by simply 10 pressing the pawl tipper back into its short nail position against the tension of the spring 696. One of the advantages of being able to start the machine with the horn in its depressed position is that, when it is desired 15 to empty the hoppers or raceways, the machine may be run to throw out the nails in the raceway without having this operation interfered with by the horn.

Having now described my invention what 20 I claim as new and desire to secure by Letters Patent of the United States is:—

1. In a machine for inserting fastenings, fastening inserting mechanism, means for supplying fastenings thereto, a work support 25 movable between work receiving and work supporting positions, a single manually controlled means for moving said work support from work receiving position to work supporting position and then actuating 30 said inserting mechanism, and means operatively connected to said fastening supplying means constructed and arranged to actuate said inserting mechanism without moving said work support.

35 2. A machine for inserting fastenings, comprising fastening inserting mechanism, mechanism for supplying fastenings thereto, a work support movable between work receiving and work supporting positions, a single manually controlled means for moving 40 said work support from work receiving position to work supporting position and then actuating said machine, and means operatively connected to one of said mechanisms operable to actuate said machine without moving said work support.

45 3. In a machine for inserting fastenings, fastening inserting mechanism, a plurality of fastening guides movable successively 50 into operative relation to said inserting mechanism and a single manually controlled means arranged to effect in succession a selective movement of said fastening guides and the actuation of said inserting mechanism.

55 4. In a machine for inserting fastenings, fastening inserting mechanism, a plurality of fastening guides arranged to be moved successively into operative relation to said 60 inserting mechanism, mechanism for automatically effecting fastening selecting movements of said guides in accordance with the demands of the work, and manually controlled means for varying the operation of

said automatic means at the will of the operator.

5. In a machine of the class described, the combination with inserting mechanism of two nail raceways constructed respectively for long and short nails and movable alternately into operative relation to said inserting mechanism, mechanism for automatically controlling and effecting said movements of the raceways in accordance with the demands of the work with respect to 75 thickness, and manually controlled means for varying the operation of said automatic means while the machine is in operation.

6. In a machine for inserting fastenings, fastening inserting mechanism, a plurality of fastening guides arranged to be moved successively into operative relation to said inserting mechanism, mechanism for automatically effecting fastening selecting movements of said guides in accordance with the 80 demands of the work, treadle operated means for varying the operation of said automatic means at the will of the operator, and treadle operated means for actuating said fastening inserting mechanism, said two 85 means being so located with respect to each other that they may be operated by a single foot of the operator.

7. In a machine for inserting fastenings, fastening inserting mechanism, a work support movable between work receiving position and work supporting position, a treadle and means whereby said treadle operates to actuate said fastening inserting mechanism and to move said work support into work 100 supporting position, a plurality of fastening guides arranged to be moved successively into operative relation to said inserting mechanism, mechanism for automatically effecting fastening selecting movements of 105 said guides in accordance with the demands of the work, a second treadle and connections between said second treadle and said automatic mechanism for varying the action of said automatic mechanism, said two 110 treadles being so located that they may be operated by a single foot of the operator.

8. In a machine for inserting fastenings, fastening inserting mechanism, a plurality of fastening guides arranged to be moved 115 successively into operative relation to said inserting mechanism, mechanism for automatically effecting fastening selecting movements of said guides in accordance with the demands of the work, and manually controlled means for effecting fastening selecting movements of said guides at the will of the operator.

9. In a machine for inserting fastenings, fastening inserting mechanism, a plurality of fastening guides arranged to be moved 120 successively into operative relation to said inserting mechanism, mechanism for auto-

matically effecting fastening selecting movements of said guides in accordance with the demands of the work, and treadle controlled means for effecting fastening selecting movements of said guides at the will of the operator.

In testimony whereof I have signed my

name to this specification in the presence of two subscribing witnesses.

GEORGE GODDU.
